BROILER DRAWER

George E. Pickup, Newark, Ohio, assignor to The Wehrle Company, Newark, Ohio, a corporation of Ohio

Application December 24, 1931, Serial No. 582,953

5 Claims. (Cl. 126—41)

The invention relates generally to cooking stoves and more particularly to a sliding broiler drawer construction for such stoves wherein the body of the broiler drawer is slidably supported on a slideable carrier so as to provide for an appreciable amount of movement of the broiler drawer out of the stove body.

The primary object of the present invention is to provide an improved broiler drawer of this character.

Another object is to provide a broiler drawer of this character wherein movements of the broiler body on the extension carrier, and movements of the carrier relatively to the stove body are controlled by actuation of the door of the broiler compartment.

Another object is to provide an improved broiler construction of the extension carrier type wherein the door for the broiler compartment is mounted on the outer end of the extension carrier for movement relative thereto and is arranged in such relative movement to control the position of the broiler body on the carrier.

Other objects and advantages will become apparent from the following description taken in connection with the accompanying drawings which illustrate the preferred embodiment of the invention, and in which:

Figure 1 is a fragmental vertical sectional view taken through a stove embodying the features of the invention, and showing the broiler in its withdrawn position.

Fig. 2 is a similar view showing the broiler positioned within the stove.

Fig. 3 is a fragmental view taken in plan section and showing the parts in the same relation as in Fig. 1.

Fig. 4 is a front elevational view showing the parts in the same relation as in Fig. 1.

Fig. 5 is an enlarged fragmental sectional view taken along the line 5—5 of Fig. 2.

In the form chosen for disclosure the invention is embodied in a stove having a compartment 10 formed by side and rear walls 11 and 12 and having at its forward side a door frame 13 with a door opening 14 therein. Within the compartment 10 a broiler body 15 is supported for movement horizontally out of the compartment through the opening 14 from the position of Fig. 2 to the position shown in Fig. 1. The broiler body 15 is preferably open at the front and is formed from sheet metal to provide upstanding side walls 16 with brackets 17 thereon so that a broiler pan or rack 18 may be inserted horizon-

tally into the broiler body so as to be supported by any desired pair of brackets 17.

The preferred form of support for the broiler body 15 embodies a slideable carrier 19 mounted in the compartment 10 for movement to the projecting position of Fig. 1, and upon which carrier the broiler body 15 is mounted for sliding movement to an overhanging position such as that shown in Fig. 1, beyond the end of the carrier. To control the shifting movement of the broiler body 15 on the carrier 19, and serve as a closure for the open end of the broiler body and for the opening 14, a door 21 is pivoted on the forward end of the carrier and is provided with bracket arms 22 rigid therewith which, through the medium of links 23, serve to reciprocate the broiler body on the carrier. Thus by grasping a handle 24 on the door 21, the operator may withdraw the carrier 19 to the projecting position of Fig. 1 while maintaining the door 21 in its vertical position so that the forward end of the broiler body 15 remains closed and the broiler body is maintained in the same relation to the carrier 19 as is shown in Fig. 2. If the operator then desires to withdraw the broiler body 25 a greater distance, the door 21 is dropped to the horizontal position of Fig. 1, which movement through the arms 22 and links 23 causes shifting of the broiler body outwardly of the compartment and along the carrier 19.

In the form illustrated, the carrier 19 consists in two elongated side members 25 of L-shaped cross section (Fig. 5) maintained in spaced relation at opposite sides of the compartment 10 by transverse struts 26 connecting the ends of the two members 25, and the carrier is supported and guided for horizontal movement by horizontal guide member rails 27 mounted in the compartment 10 on opposite sides thereof. The carrier 19 is preferably supported adjacent the forward ends of the rails 27 by means of rollers 28 mounted on the guide rails 27 and engaging horizontally projecting flanges 25a (Figs. 4 and 5) of the side members 25. At its rear or inner end the carrier 19 engages the guide rail 27 so as to prevent appreciable movement in either an upward or downward direction whereby to render the carrier effective as a projecting or cantilever support for the broiler body when positioned as in Fig. 1. For this purpose each end 26a of the rear strut 26 (Fig. 5) extends over an inwardly projecting horizontal flange 27a formed on the adjacent guide rail 27, and a bracket 29 connected to the strut 26 extends beneath the flange 27a.

27^a and is fixed to the side member 25 of the carrier.

Support for the broiler body 15 on the carrier 19 is provided in a similar manner by rollers 30 mounted on the inner sides of the side members 25 adjacent the forward ends thereof and arranged to engage flat surfaces 31 (Figs. 4 and 5) on the broiler body 15 provided by inwardly offsetting the lower portion of the side walls 16 thereof. 10 This construction provides space for the supporting means and yet it permits the broiler body to be of the maximum depth. At its rear or inner end, the broiler body 15 is held against vertical displacement by guide members 32 formed from sheet metal straps bolted at 33 to the bottom of the broiler body and extending beneath the side members 25 as shown in Fig. 5, and each provided with a part 32^a engaging the upper surfaces of the flanges 25^a of the side members. The outer 15 ends of the guide members 32 are bent upwardly as at 34 along the outer sides of the members 25 so as to be located between the members 25 and the guide rails 27.

In the preferred mounting of the door 21, the 25 bracket arms 22 are secured adjacent the opposite ends of the door and close to the lower edge thereof so that the arms 22 project along the outer sides of carrier 19. The arms are pivoted to the carrier at 35 spaced a substantial distance from 30 the inner face of the door so that the door is, in all of its positions, located a substantial distance from the end of the carrier. Thus when the door 21 is swung about the pivotal axis 35, it moves downwardly at a rate which causes it to move 35 clear of the outwardly moving broiler body 19. The arms 22 extend a substantial distance beyond the pivotal axis 35 and are pivoted at 36 (Fig. 1) to the ends of the links 23. The links 23, in turn, extend rearwardly along the sides of the broiler 40 body and are pivotally connected at 37 to the up-standing ends 34 of the guide members 32. In order to clear the path of the links 23, the flanges 27^a terminate substantially at the mid-points of the rails 27, as indicated at 38 in Figs. 1 and 3.

45 To limit the withdrawing movement of the carrier 19, each side member 25 carries a stop 39 (Figs. 1 and 2) adapted to engage the rollers 28, and if desired a depending guard 40 may also be associated with each side member 25 so as to enclose the rollers 28 when the carrier is withdrawn.

50 From the foregoing it will be apparent that the invention provides a broiler drawer wherein the door or end closure of the drawer serves as a removable closure for the forward end of the broiler body as well as for the compartment door opening. It will also be clear that the novel association of the elements of the device provides a considerable range of movement for the broiler body, and throughout this entire range, the movement 55 is controlled by one handle carried by the door.

I claim as my invention:

1. A broiler comprising, in combination, a compartment having a front opening, an extension slide mounted in said compartment for movement 60 through said opening, a broiler body mounted on said slide for relative movement beyond the outer end of the slide, a closure member for said opening having spaced bracket arms on its inner side positioned adjacent to opposite sides of said slide, 65 means pivoting said arms to the forward end of the slide on an axis spaced from the inner face of said door and from the ends of said arms whereby to permit pivotal movement of said door to a horizontal position below the level of said broiler 70 body, a pair of links, each of which is pivotally 75

connected at one end to the inner end of one of said arms, and means pivotally connecting the other ends of said links to said broiler body whereby to shift said broiler body outwardly on said slide when said door is pivoted to its horizontal 80 position.

2. In a broiler, the combination of a compartment having a forward opening, a carrier mounted in said compartment for sliding movement through said opening, a broiler body having an open forward side and mounted on said carrier for movement on said carrier to a position in which it projects beyond the end of said carrier, brackets on opposite sides of said broiler body, a rack movable onto said brackets through said open forward side of the broiler body, a member for closing the forward side of said body and for closing said compartment opening, means pivotally securing said closure member on the end of said carrier for movement from a vertical position 20 to a horizontal position, an arm fixed to said closure member and projecting substantially perpendicularly therefrom along one side of said broiler body, and a link connecting the end of said arm with said broiler body operable to shift said 25 member pivoted to its horizontal position.

3. In a stove having a compartment with a forward opening, the combination of a carrier, rollers mounted in the forward portion of said compartment and supporting said carrier, guide rails in said compartment along opposite sides of said carrier, said rails having inwardly projecting flanges along their upper edges, means on the rear end of said carrier straddling said flanges 35 to determine the vertical position of the rear end of the carrier, a broiler body mounted on said carrier for relative movement parallel to the path of said carrier and beyond the forward end thereof, a door for closing said opening, a pair of 40 brackets secured to said door and extending inwardly from the door along the sides of said carrier, means pivoting said brackets to the carrier on an axis spaced from said door and from the ends of said brackets, a pair of links each 45 having one end pivoted to the end of one of said brackets, and each link having its other end pivoted to said broiler body below the plane of said flanges, said flanges being terminated a substantial distance from the forward end of said rails 50 to provide clearance for said links.

4. A broiler comprising, in combination, a compartment having a front opening, an extension slide mounted in said compartment for movement through said opening, a broiler body mounted on said slide for movement longitudinally on the slide outwardly beyond the outer end of the slide, a closure member pivotally mounted on the outer end of said slide for movement into a horizontal open position out of the path of movement 60 of said broiler body, and operating linkage connecting said closure and said body proportioned to impart smooth increasingly greater outward movement to said body as the closure approaches horizontal open position and to impart decreasing 65 inward movement as the closure is swung from horizontal open to closed position, said linkage including an arm rigid with the closure and extending a substantial distance perpendicularly therefrom and a link member pivotally connected 70 to said arm and to said body.

5. A broiler construction comprising, in combination, a compartment having a front opening, an extension slide mounted in said compartment for movement through said opening, a broiler 75

body slidably mounted on said slide for substantial reciprocal movement one limit of which is longitudinally outwardly beyond the forward end of the slide, operating linkage beside said broiler body for effecting forwardly sliding movement of said broiler body relative to said slide and including a pair of pivoted members, means forming a rigid part of said broiler body pivotally connected directly with the free end of one of said mem-

bers so that movement of said member will correspondingly move said body, means pivotally connecting the other member on a fixed axis directly upon the side of said slide, and manual means for operating said linkage to cause pivotal movement of said members, whereby said one member is moved forwardly and said broiler body is drawn reciprocally along said slide.

GEORGE E. PICKUP.
